UNITED STATES PATENT OFFICE.

FRANCIS M. BARTON, OF CHICAGO, ILLINOIS, ASSIGNOR TO BARTON SPIDER-WEB SYSTEM, OF CHICAGO, ILLINOIS, A CORPORATION OF ILLINOIS.

METALLIC REINFORCEMENT FOR CONCRETE STRUCTURES.

Application filed November 28, 1919. Serial No. 341,095.

To all whom it may concern:

- Be it known that I, FRANCIS M. BARTON, a citizen of the United States, and a resident of Chicago, in the county of Cook and 5 State of Illinois, have invented certain new and useful Improvements in Metallic Reinforcements for Concrete Structures, of which the following is a full, clear, and exact description.
- 10 The invention relates to metallic reinforcement for concrete structures. The object of the invention is to provide improved devices for securing crossed rods of reinforcement together.
- 15 It has heretofore been proposed to use continuous strips for holding crossed rods, such, for example, as are used in helicoidal column-reinforcement, in properly spaced relation. In practice, it has been found that 20 the use of long bars for this purpose is objectionable, because of the difficulty in simultaneously placing and securing a large number of crossing rods in position.
- One object of the invention is to provide 25 an improved reinforcement for securing crossed rods or bars together in which the securing-means comprises a series of clips which may be serially placed in position and which, besides being provided with 30 means for holding crossed rods together, is provided with means for positioning and spacing the holding devices so that when these devices are serially secured along one rod, an entire series of crossing rods will be 35 locked in properly spaced relation.
- The invention consists in the several novel features hereinafter set forth and more particularly defined by claims at the conclusion hereof.
- 40 In the drawings: Fig. 1 is a side elevation of a floor reinforcement embodying the invention. Fig. 2 is a plan. Fig. 3 is a section taken on line 3—3 of Fig. 1. Fig. 3^a is a section taken on line 3^a—3^a of Fig. 45 1. Fig. 3^b is a section taken on line 3^b—3^b of Fig. 1. Fig. 4 is a perspective of one of the clips for securing cross-rods together. Fig. 5 is a perspective of a clip which is adapted to hold two crossing rods. Fig. 6 50 is a perspective of a reinforcement embodying the invention. Fig. 7 is a perspective of a column reinforcement embodying the invention. Fig. 8 is a detail perspective of a portion of the reinforcement shown in

Fig. 7. Fig. 9 is a perspective of a modified 55 form of the invention.

In Figs. 1 to 6, the invention is exemplified in a floor reinforcement comprising crossed rods 10 and 11 and a series of clips 12 of round wire for securing the crossed rods together and in properly spaced relation. Each clip 12 comprises a hook 13 at one end adapted to extend under the rod 10, a portion 14 adapted to extend longitudinally of said rod, a loop 15 adapted to receive one of the crossing rods 11 to space and hold it at the desired point on rod 10, and loops forming upstanding tongues or projections 16 and 17 which are connected by a loop 18. Each clip 12 is provided, between its hook 13 and its loop 15, with laterally extending opposed loops 19 and 20 which are adapted to pass around and between the tongues 16 and 17 of the next clip and thus form a longitudinal and lateral 75 interlock between the adjacent ends of the clips. These loops 19 and 20 are also adapted to overlie and engage portions of the adjacent clip and thus lock the latter down against the rod 10. The loop 18 of each 80 clip is extended downward to form a leg adapted to rest on temporary staging 21 and the lower end of each loop 17 is also extended downwardly to form a similar leg, and these legs are adapted to support the 85 reinforcement in spaced relation to the staging.

In laying the reinforcement, the hook 13 at one end of the clip 12 is first connected to the rod 10. This can be done by slipping the hook laterally around the rod 10 while the clip is tilted relatively to said rod, the hook 13 being inclined relatively to the longitudinally extending portion 14 so that this connection can be easily effected 90 while the hook is tilted, so that the hook will be substantially at right angles to said rod. The crossing rod 11 to be held by the clip is placed into position to enter the loop 15 and then the clip is swung downwardly 100 to bring the longitudinal portion 14 against or along side of the rod 10. This will bring the lower end of loops 17 and 18 into position to support the reinforcement and loops 16 and 17 will be in position to be locked 105 to the rod 10 by the next clip. The next clip is then connected to the rod 10 in like manner, its hook being slipped under the

- rod 10 while the clip is in tilted position. When the latter clip is swung downwardly to bring its longitudinal portion 14 along side of the rod 10, the loops 16 and 17 will 5 pass between the lateral loops 19 and 20 of the second clip and will pass around the loops 16 and 17 of, and will overlie, the first clip so that the hook end of the second clip will lock the adjacent end of the first clip 10 against separation from the rod 10 and will also be interlocked against relative longitudinal movement and lateral movement. As many clips as desired may be serially applied to the rod 10.
- 15 This construction exemplifies a reenforcement in which the crossed rods are secured together in properly spaced relation by clips which are interlocked to relatively space one another and which are provided with means 20 to hold and space the crossing rods. The construction also exemplifies such a reenforcement in which each clip is adapted, with a hook at one end, to engage the rod and with means at its other end which is 25 adapted to be locked to the rod by the hook of the next adjacent clip. An important advantage of this construction is that the crossing rods and clips may be successively applied to the longitudinal rod and in this 30 manner the work of assembling the reenforcement is greatly expedited.

In Fig. 5, the clip 12' is similar in construction to the clips hereinbefore described, except that it is provided with a plurality of 35 loops 15^a so that each clip will serve to hold and space a plurality of crossing rods 11.

In Figs. 7 and 8, the invention is illustrated as applied to a column-reenforcement comprising a series of helicoidal members 40 11^a and longitudinal rods 10^a. The clips are similar in construction to those hereinbefore described, except that in some instances the loops 15^b are adapted to receive the lapped ends 11^b of the helicoidal reenforcing 45 member.

In the construction shown in Fig. 9, a plate 25 is adapted to be slipped over the end of the rod 10 to lock the clip 12^c at the end of the series of clips or adjacent the end of 50 the rod 10 to said rod.

The invention is not to be understood as restricted to the details set forth, since these may be modified within the scope of the appended claims, without departing from the 55 spirit and scope of the invention.

Having thus described the invention, what I claim as new and desire to secure by Letters Patent, is:

- 60 1. In reenforcement for concrete structures, the combination of a rod, a series of crossing members, and clips extending lengthwise of the rod, provided with means whereby they may be secured to the rod and with means for holding crossing members in 65 relation to the rod and with portions formed

to interlock with portions of an adjacent clip and whereby clips will be held against relative longitudinal movement independently of the crossing members.

2. In reenforcement for concrete structures, the combination of a rod, a series of 70 crossing members and clips for securing the crossing members to the rod, provided with portions formed to directly interlock with portions of an adjacent clip and secure the 75 clips against relative longitudinal movement.

3. In reenforcement for concrete structures, the combination of a rod, a series of 80 crossing members, and clips provided with means whereby they will be secured to the rod with means for holding crossing members relatively to the rod and overlapping portions for securing the contiguous ends of adjacent clips on the rod for spacing 85 adjacent clips from one another longitudinally of the rod independently of the crossing members.

4. In reenforcement for concrete structures, the combination of a rod, a series of 90 crossing members, and clips provided with means for securing them on the rod, with loops for securing the members relatively to the rod, and provided with interlocking portions securing adjacent clips on and for 95 spacing one another longitudinally of the rod, independently of the crossing members.

5. In reenforcement for concrete structures, the combination of a rod, a series of 100 crossing members, and clips provided with means for securing one end of each clip to the rod, loops for securing the members on the rod, additional loops, and tongues on their other ends, the tongues and additional 105 loops on the contiguous ends of adjacent loops interfitting and overlapping one another to secure the clips on and space them longitudinally of the rod.

6. In reenforcement for concrete structures, the combination of a rod, of a series 110 of crossing members and clips having means for securing the members relatively to the rod, and interlocking means between the clips whereby they will be secured against relative longitudinal movement.

7. In reenforcement for concrete structures, the combination of a rod, of a series 120 of crossing members and wire clips having means for securing the members relatively to the rod, and interlocking loops between the clips whereby they will be secured against relative longitudinal movement.

8. In reenforcement for concrete structures, the combination of a rod, of a series 125 of crossing members and clips having means for securing the members relatively to the rod and interlocking means between the clips whereby the clips will be secured against relative lateral movement. 130

9. In reenforcement for concrete structures, the combination of a rod, of a series of crossing members and wire clips having means for securing the members relatively to the rod and interlocking loops between the clips whereby the clips will be secured against relative lateral movement.
10. In reenforcement for concrete structures, the combination of a rod, a series of crossing members and clips having means for securing the members relatively to the rod and interlocking means between the clips whereby the clips will be secured against relative lateral and longitudinal movement.
11. In reenforcement for concrete structures, the combination of a rod, a series of crossing members and wire clips having means for securing the members relatively to the rod, and interlocking loops between the clips whereby they will be secured against relative lateral and longitudinal movement.
12. In reenforcement for concrete structures, the combination of a rod, a series of crossing members and a series of clips, the latter having hooks at one end for engaging the rod, means to hold a crossing member, a longitudinally extending portion, and means at the other end adapted to interlock with an adjacent clip.
13. In reenforcement for concrete structures, the combination of a rod, a series of crossing members and a series of clips, the latter having hooks at one end for en-
- gaging the rod, a loop to hold a crossing member, a longitudinally extending portion, and means at the other end adapted to interlock with an adjacent clip.
14. In reenforcement for concrete structures, the combination of a rod, a series of crossing members and clips disposed longitudinally along the rod and provided with means to secure a crossing member to the rod, the clips being provided with means for serially securing one another to the rod and with interlocking means therebetween.
15. In reenforcement for concrete structures, the combination of a rod, a series of crossing members and clips disposed longitudinally along the rod and provided with means to secure a crossing member to the rod, each clip being provided with a single open sided hook at one end for engaging the rod and means at the other end adapted to straddle the rod and secure it against lateral movement relative to the rod.
16. In reenforcement for concrete structures, the combination of a rod, a series of crossing members and clips disposed longitudinally along the rod and provided with means to secure a crossing member to the rod, each clip being provided with a hook at one end for engaging the rod and means at the other end adapted to straddle the rod and secure it against lateral movement relative to the rod and with means to interlock with an adjacent clip.

FRANCIS M. BARTON.
